(57) **CLAIM**

The ornamental design for body of ultrasonic diagnostic equipment, as shown and described.

DESCRIPTION

FIG. 1 is a perspective view of body of ultrasonic diagnostic equipment, showing a new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a perspective view thereof showing the body of ultrasonic diagnostic equipment in an alternative configuration and in an environment in which it may be used.

The broken lines are included for the purpose of illustrating portions of the body of ultrasonic diagnostic equipment that form no part of the claimed design.
